Primary Examiner — Paula Greene*(74) Attorney, Agent, or Firm* — LambertIP**CLAIM**

The ornamental design for a pair of earbuds, as shown and described.

DESCRIPTION

FIG. 1 is a perspective view of the left and right earbuds of a pair of earbuds showing, our design.

FIG. 2 is a front view of the right earbud, the front view of the left earbud being a mirror image thereof.

FIG. 3 is a rear view of the right earbud, the rear view of the left earbud being a mirror image thereof.

FIG. 4 is a right side view of the right earbud, the left side view of the left earbud being, a mirror image thereof.

FIG. 5 is a left side view of the right earbud, the right side view of the left earbud being a mirror image thereof.

FIG. 6 is a top view of the right earbud, the top view of the left earbud being a mirror image thereof; and,

FIG. 7 is a bottom view of the right earbud, the bottom view of the left earbud being, a mirror image thereof.

The broken lines showing the environment in FIGS. 1-7 are included for illustrative purposes only and form no part of the claimed design.
